or A. R. Farnoess.

1,029,869. CAR-TRUCK FRAME. CLARENCE H. HOWARD and HARRY M. PFLAGER, St. Louis, Mo., assignors to Double Body Bolster Company, St. Louis, Mo., a Corporation of New Jersey. Filed Dec. 13, 1911. Serial No. 665,579.

To all whom it may concern:

Be it known that we, CLARENCE H. HOWARD and HARRY M. PFLAGER, citizens of the United States, residing at St. Louis, Missouri, have invented a certain new and useful Improvement in Car-Truck Frames, of which the following is a full, clear, and exact description, such as will enable others skilled in the art to which it appertains to make and use the same, reference being had to the accompanying drawings, forming part of this specification, in which—

Figure 1 is a top plan view of a truck frame of our improved construction. Fig. 2 is a plan view partly in horizontal section of one side of a truck frame of our improved construction. Fig. 3 is a section taken on the line 3--3 of Fig. 1. Fig. 4 is an enlarged cross section taken approximately on the line 4--4 of Fig. 1.

This invention relates generally to car truck frames of the type which are cast or formed in a single piece, and more particularly to the means for connecting the upper portions of the swing hangers to the truck frame.

The principal objects of our invention are to provide strong, substantial bearings for the upper ends of the swing hangers at the ends of the transoms of the truck, and to reinforce the transoms adjacent to the bearings for the swing hangers in order to fully overcome all strains and stresses which may be imparted to the truck frame by said swing hangers while in service.

To the above purposes our invention consists in certain novel features of construction and arrangement of parts hereinafter more fully described and claimed.

In the drawings we have illustrated a four-wheel cast metal truck frame the same comprising the side or wheel pieces 1 and the transversely disposed inner transoms 2 and outer transoms 3. These transoms are preferably channel shaped in cross section, each comprising a vertically disposed web having outwardly projecting top and bottom flanges. The ends of the horizontally disposed bottom flanges of the inner pair of transoms are widened as designated by 4 and formed through the central portions of these widened ends are apertures 5 through which the upper ends of the swing hangers are adapted to pass. Formed integral with

the widened end portions 4 adjacent the openings 5 are vertically disposed webs 6 which occupy positions parallel with the vertical webs of the inner transoms 2, and formed through these vertical webs 6 and the vertical webs of the inner transoms 2 immediately above the openings 5 are apertures 7 which are in horizontal alignment with one another. If desired these apertures 7 may be provided with bushings 8, although this construction is not absolutely essential. Uniting the upper portion of each web 6 with the adjacent vertical web of the inner transom is a horizontally disposed web 9. The vertically disposed web 6 and horizontally disposed web 9 combine to form an inverted L-shaped housing directly over the opening 5, which housing materially strengthens the vertical web and bottom flange of the transom, and the vertical web 6 provided with the opening 7 forms a bearing for one end of the pin or bolt

from which the swing hanger A is suspended.

The construction just described forms very strong, substantial bearings for the upper ends of the swing hangers A which, as hereinbefore stated, project through the openings 5 and receive horizontally disposed pins B which extend through openings formed in the upper ends of said swing hangers and through the bushings in the openings 7. The webs 6 are connected with the vertical webs of the inner transoms by the webs 9 which extend horizontally with said transoms, thereby avoiding any crossed connecting members between the adjacent inner and outer transoms, which latter construction is difficult to cast besides being liable to cause shrinkage cracks which materially weaken castings of this character. The end portions of the bottom flanges of the inner transoms are widened in order to provide ample strength for the transoms at the points where the swing hangers are suspended, and such widening makes up for the metal removed by the formation of the openings 5 in said bottom flanges.

When in service car truck frames are subjected to strains due to constant movement of the swing hangers lengthwise of the truck, which movement causes corresponding movement to all of the swing hanger members, and, as a result, the metal in the transoms of the truck frame is gradually fatigued, and to overcome this action the ends of the inner transoms are widened and extra wide gusset plates between the ends of the transoms and the wheel or side pieces of the frame are utilized, thereby bringing both transoms into action at the same time to resist the strains due to the backward and

forward swinging action of the hangers.

It will be readily understood that minor changes in the size, form and construction of the various parts of our improved truck frame can be made and substituted for these shown and herein described without departing from the spirit of our invention, the scope of which is set forth in the appended claims.

We claim:

1. A cast metal truck frame provided with transoms having openings in their bottom flanges adapted to receive the upper ends of swing hangers, and inverted L-shaped reinforcing members integral with said transoms immediately over said openings.

2. A cast metal truck frame provided with transoms having the bottom flanges widened at the ends and which widened end portions are provided with openings adapted to receive the upper ends of the swing hangers, vertically disposed webs integral with the widened portions of the bottom flanges of

the transoms and there being openings formed through said webs and through the webs of the transoms, which openings are adapted to receive the pins on which the swing hangers are journaled.

3. The herein described truck frame having channel shaped transoms in the end portions of the bottom flanges of which are formed openings for the swing hangers, webs integral with the bottom flanges adjacent the swing hanger openings and there being aligned openings formed through said webs and through the webs of the transoms, which aligned openings are adapted to receive pins from which the swing hangers are suspended.

4. The herein described cast metal truck frame having transoms in the end portions of the bottom flanges of which are formed openings for the swing hangers of the truck, webs integral with the bottom flanges of the transoms adjacent the openings therein, there being aligned openings in said webs and the webs of the transoms for the pins from which the swing hangers are suspended and horizontally disposed webs connecting the upper portions of the vertically disposed webs of the transoms.

5. The herein described cast metal truck frame provided with transoms having widened end portions through which are formed openings for the swing hangers, vertically disposed webs integral with the widened end portions of the transoms adjacent the openings therein, there being openings formed in said webs and in the webs of the transoms, which openings receive the pins from which the swing hangers are suspended and horizontally disposed webs integral with and connecting the upper por-

tions of the vertically disposed webs and the webs of the transoms.

6. The herein described cast metal truck frame having transoms which are channel shaped in cross section and the bottom flanges of which transoms are provided at their end portions with openings adapted to receive the upper portions of the swing hangers, webs on the bottom flanges of the transoms adjacent the openings therein, there being openings formed in said webs and in the webs of the transoms for the suspension pins of the swing hangers and horizontally disposed flanges connecting the upper portions of the webs on the bottom flanges of the webs of said frames.

7. In a car truck frame a transom having a bottom flange provided through its end portion with openings adapted to receive the upper ends of swing hangers, inverted L-shaped reinforcing members integral with the transom immediately over the openings therein, and the vertical walls of which reinforcing members are provided with bearings for the swing hanger supports.

8. In a car truck frame, a transom having openings formed through its bottom flange adapted to receive the upper ends of the swing hangers, webs integral with the bottom flange adjacent the openings therein and horizontally disposed webs uniting the upper portions of the first mentioned webs with the body portion of the transom.

9. In a car truck frame, a transom having a bottom flange through which is formed openings adapted to receive the upper ends of swing hangers, and vertically disposed walls integral with the bottom flange adjacent to said openings, which walls are provided with bearings for the swing hanger supports.

10. In a car truck frame, a transom having a bottom flange through which is formed openings adapted to receive the upper ends of swing hangers, vertically disposed walls integral with the bottom flanges adjacent to said openings, and horizontally disposed plates integral with the upper ends of said plates and with the web of the transom.

11. A cast metal truck frame comprising wheel pieces, a pair of outer transoms, a pair of inner transoms the bottom flanges of which inner transoms are provided with openings adapted to receive the upper ends of the swing hangers and means above said openings for receiving the members from which the swing hangers are suspended.

In testimony whereof we hereunto affix our signatures in the presence of two witnesses, this 2nd day of December, 1911.

CLARENCE H. HOWARD.

H. M. PFLAGER.
